DESIGN FOR A SHOE

Alphons Hurzeler, New Rochelle, N. Y.

Application September 23, 1937, Serial No. 71,746

Term of patent 3½ years

To all whom it may concern:

Be it known that I, Alphons Hurzeler, a citizen of Switzerland, residing in New Rochelle, in the county of Westchester and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

I claim:

The ornamental design for a shoe substantially as shown.

ALPHONS HURZELER.
